UNITED STATES PATENT OFFICE.

FRANK D. BLAIR, OF MOUND, MINNESOTA.

RADIO LOG AND INDICATING DEVICE.

Application filed January 15, 1925. Serial No. 2,558.

To all whom it may concern:

Be it known that I, FRANK D. BLAIR, a citizen of the United States, residing at Mound, in the county of Hennepin and State of Minnesota, have invented certain new and useful Improvements in a Radio Log and Indicating Device; and I do hereby declare the following to be a full, clear, and exact description of the invention, such as will 10 enable others skilled in the art to which it appertains to make and use the same.

This invention relates to a radio receiving set and particularly to a device used in conjunction with a tuning control member 15 of such set and co-operating with such member to form a log of stations received and to form an identification means of the stations received. It has heretofore been the common practice to have movable tuning 20 control members on receiving sets and have numbered graduations past which said members were moved. When the tuning member or members were adjusted for certain stations a record could be made of the numbers alined with the said member or members and the operator could then keep a log 25 of the stations received and the positions of the tuning member therefor. Such a log was kept on a separate card or book and the 30 use thereof is quite inconvenient.

It is an object of this invention, therefore, to provide means co-operating with a tuning control member adapted to receive identification members of various stations so that 35 said latter members will at once indicate the station, and the tuning control member can quickly be positioned for such station by merely being turned into alinement with said identification member.

It is a further object of the invention to provide a plate disposed about the path of the tuning control member, which plate has formed therein a multiplicity of small channels or sockets, which channels or sockets are 45 adapted to have inserted therein small identification members bearing the name or indication of a station received.

It is more specifically an object of the invention to provide a plate adapted to be disposed about the path of a swinging tuning control member having formed therein a multiplicity of radially disposed channels adapted to receive identification members, said plate and control members also having 55 inner engaging means for holding said con-

trol member in position in alinement with one of said channels.

These and other objects and advantages of the invention will be fully set forth in the following description made in connection 60 with the accompanying drawings in which like reference characters refer to the same parts throughout the different views, and in which,

Fig. 1 is a view in front elevation of the 65 device;

Fig. 2 is a view as seen from the side of Fig. 1, a portion thereof being broken away;

Fig. 3 is a fragmentary vertical section taken on the line 3—3 of Fig. 1, as indicated 70 by the arrows;

Fig. 4 is a fragmentary vertical section taken on the line 4—4 of Fig. 1, as indicated by the arrows;

Fig. 5 is a face view of one of the identi- 75 fication members used;

Fig. 6 is a view in front elevation of a modified form of the device;

Fig. 7 is a view in horizontal section taken on the line 7—7 of Fig. 6; 80

Fig. 8 is a section taken substantially on the line 8—8 of Fig. 1, showing a specific modified structure of the plate used.

Referring to the drawings, a cabinet 10 is shown having a front wall 10^a, a base 85 10^b and a rear wall 10^c, the latter being shown as hinged at its lower edge so as to swing outwardly. The cabinet 10 may form the ordinary cabinet which encloses the receiving apparatus of a receiving set or it 90 may represent a cabinet having therein only a portion of the apparatus, such as the parts which are moved for tuning, such as the condensers or vario-couplers. If the cabinet is used merely for adjusting parts, 95 the same will be provided with a pair of binding posts 11, by means of which said parts can be connected to the rest of the apparatus which will usually be disposed in a separate cabinet. While the cabinet 10 may 100 take various shapes, in the embodiment of the invention illustrated, the same is shown as having a vertical rear wall and an upwardly inclined front wall or panel 10^c. Whether the cabinet is used as containing all 105 of the apparatus or only part thereof, the same will be provided with a tuning control member 12, which, in Fig. 1, is shown as oscillatable about a fixed axis and regulating a tuning apparatus 13 shown in 110

dotted lines. In accordance with the present invention a plate 14 is disposed against the face of panel 10^a and about the path of the swinging member 12. While the plate 14 may take various shapes, depending upon the path of the tuning control member, in the embodiment of the invention shown in Fig. 1, said plate is of semi-annular form and is of approximately 180 degrees in extent. The plate 14 has formed therein a multiplicity of radially disposed channels or sockets 14^a and said plate has disposed in front thereof, a member 15 of transparent material, such as glass or celluloid, said member being of the same shape as plate 14. While the members 14 and 15 may be secured to the panel and held thereon in any suitable manner, in the embodiment of the invention illustrated the same are shown as supported and held in place by an angle member 16, said member having a semi-circular portion disposed within and overlapping the outer edge of the concave side of members 14 and 15 and extending along and overlapping the bottom side thereof, said member 16 being shown as secured to panel 10^a by suitable screws. The member 16 has small holes or depressions 16^a spaced about its semi-circular portion with which a projection 12^a on the member 12 co-operates, said member 12^a preferably being resiliently pressed toward said member 16 and being controlled by a handle knob 17 by which the member 12 may be moved. The holes 16^a are aligned substantially centrally with the channels 14^a. The channels or sockets 14^a are adapted to receive and have inserted therein from their outer ends small flat identification members 18, which members preferably will be of sheet material such as metal, celluloid, bone, heavy paper, etc., and which will bear inscriptions containing the designations or names of radio sending stations. It will be noted that the ends of members 18 are similarly formed so that either end thereof can be inserted in the sockets or channels 14^a.

In the modification shown in Figs. 7 and 8, a movable tuning control member 20 is shown movable in a slot 21^a formed in a panel 21, which panel forms the front of a rectangular cabinet 22. Said cabinet 22 may, like the cabinet 10, contain all or only part of the apparatus of a radio receiving set. The member 20 also can be moved to be connected to any desired form of tuning apparatus, but in the embodiment of the invention illustrated, the same is shown as connected to the movable plate 23 of a plate condenser, a stationary plate thereof being indicated at 24. A plate or member of sheet material 25 is secured to the panel 21 by suitable screws extending through the end portions thereof, which member 25 has a slot 25^a therethrough through which the

member 20 projects, said slot being surrounded by an outwardly extending flange 25^b. The member 25 has formed therein and extending substantially at right angles to and at each side of the flange 25^b, sockets 70 or channels 25^c, the channels at opposite sides of slot 25^a, preferably, being arranged in staggered relation. The portion of plate 25 at each side of flange 25^b is overlaid or covered with sheets 26 of transparent material, such as glass or celluloid, which may be secured to the portions of plate 25 between the channels 25^c by a suitable adhesive or by any other suitable means. The channels 25^c are adapted to receive narrow flat 80 identification members 18, such as shown in Fig. 5, which members preferably will snugly fit the channels so as to be frictionally held in position.

While the sockets 14^a and the sockets 25^c in plate 25 may be formed in the plate 14 in various ways, one convenient form of constructing said sockets is, as shown in Fig. 8. In said figure a sheet of material 19 is shown having the channels 19^a pressed therein. 90 This operation will be performed in suitable dies on a metal sheet or on a sheet of heavy paper or fibrous material.

In operation of the device as shown in Figs. 1 to 5, the operator will tune the receiving set to receive certain stations, as usual, by swinging the member 12. When a certain station is received, the member 12 will point to one of the channels 14^a. The operator will then insert in said channel an appropriate identification member 18 bearing the indication name or number of said station, and similarly, identification members 18 will be located in others of the channels 14^a. When the operator again desires to tune in for a certain station shown on one of the identification members 18 he will merely have to turn the member 12 to the position aligning with said channel and the instrument will be positioned to receive from said station. When the operator is moving the member 12 merely at random in order to pick up stations and picks up a certain station, which has been previously received he will at once see by the identification member 18 what station it is and will not have to wait to listen to the announcer for the name of the station. The device therefore not only forms a permanent log which is always in place and in sight directly on the 110 instrument but it also forms an indicator for identifying stations when received.

In the operation of the device shown in Figs. 6 and 7, the instrument will be tuned to receive certain stations by moving the member 20 rectilinearly. When a certain station is received the operator will place an identification card in the appropriate channel 25^c. This card will then form a log and will show where said station can again be 120 125 130

picked up and will indicate the station when it is picked up at such point.

From the above description it is seen that applicant has provided a very simple and efficient device for a radio receiving set and one which will have a high degree of utility in connection therewith. The device is easily placed on the panels of radio sets already in use or can be easily embodied in new sets. As above pointed out, the device can either be placed on the regular cabinet on which all of the apparatus is disposed, or be placed on a shell or cabinet having only tuning instruments therein. The device is very convenient on receiving sets having unit control or only one member which is moved for tuning. Several companies are now making such receiving sets and future sets, in all probability, will have only one tuning control member. The device is quite simple and inexpensive and can be produced at comparatively low cost. The same has been amply demonstrated in actual practice and found to be very successful and efficient. It will, of course, be understood that various changes may be made in the form, details, arrangement and proportions of the parts without departing from the scope of applicant's invention, which, generally stated, consists in the novel parts and combinations of parts disclosed and defined in the appended claims.

What is claimed is:

1. The combination with a movable tuning control member of a radio receiving set,

of a device adapted to be secured to the panel of the set having an arcuate track concentric with the path of travel of the control member and over which the control member is adapted to slide, said device having a radial series of sockets with which said control member is adapted to align, and said sockets being open at their outer ends and closed at their inner ends to receive and retain identification members bearing indicia of radio sending stations. 40 45

2. The combination with a movable tuning control member of a radio receiving set of an identification registering device having a track concentric with the path of travel of the control device and over which the control device is slidably adjusted, and an arcuate member surrounding said track and having a radial series of sockets open at their outer ends and closed at their inner ends adjacent 50 55 said track adapted to receive and retain identification members bearing indicia of radio sending stations.

3. A panel for radio tuning apparatus having a movable tuning control member mounted thereon, said panel having a radial series of sockets disposed thereon and with each of which said control member is adapted to align, said sockets being closed at their ends adjacent said control member and 60 65 open at their outer ends to receive and retain identification members bearing indicia of radio stations.

In testimony whereof I affix my signature.

FRANK D. BLAIR.
